UNITED STATES PATENT OFFICE.

BENJAMIN SUMMERS, OF PETERSBURG, ASSIGNOR OF ONE-HALF TO CALEB C. NORTH, OF HUNTINGDON, PENNSYLVANIA.

STAMP-CANCELER.

SPECIFICATION forming part of Letters Patent No. 404,574, dated June 4, 1889.

Application filed April 4, 1888. Serial No. 269,595. (No model.)

To all whom it may concern:

Be it known that I, BENJAMIN SUMMERS, of Petersburg, in the county of Huntingdon and State of Pennsylvania, have invented a new and Improved Stamp-Canceler, of which the following is a full, clear, and exact description.

Reference is to be had to the accompanying drawings, forming a part of this specification, in which similar letters of reference indicate corresponding parts in all the figures.

Figure 1 is a side elevation of my new and improved stamp - canceler. Fig. 2 is a sectional elevation of the same, taken on the line xx of Fig. 1. Fig. 3 is a plan view of the bottom of the canceler, and Fig. 4 is a transverse sectional elevation taken on the line y of Fig. 1.

The invention will first be described in connection with the drawings, and then pointed out in the claims.

A represents a plate, to which are attached blocks B B', formed with teeth for cutting and defacing the surface of the stamps. Opposite the blocks B B' is the pad C, provided with lettering and date at its lower surface to apply the post-mark to letters and other mail-matter. The lower surface of the plate A is formed at one end with the cheek-pieces A' A', to receive and hold the blocks B B', and the said plate is formed at its upper surface with the tube A², which contains the rod E, to which the handle D is applied. The rod E is loose in the tube A², and its lower end is pivoted to a triangular tumbler F, pivoted on the stud a, attached to the projection G of the plate A. The block B is attached by pivot b to the tumbler F above its pivot a, while the block B' is attached by pivot b' to said tumbler below the pivot a, so that a down-thrust of the rod E, turning tumbler F, will impart opposite horizontal movement to the blocks B B'. The teeth of the block B are slanted inward, while the teeth of the block B' are slanted outward, so that the opposite movement of the two blocks very effectively cuts and defaces the stamps beyond all restoration.

The blocks B B' may be held in the cheek-pieces A' A' in any suitable manner to permit opposite movement; but for this purpose I prefer to construct the block B to carry the block B', and to connect the block B to the

cheek-pieces A' by means of tongue-and-groove ways c c. (Shown clearly in Fig. 4.) The block B is grooved, as shown at d, to form three plates d', and the slots are enlarged to form the offsets i, as shown clearly in Fig. 4. The block B' is centrally slotted to form the plates f f, which span the central plate d' and are formed with flanges e to engage with shoulders i for connecting the block B' to the block B.

The rod E is provided at its upper end with the sleeve H, held by the nut h screwed upon the rod. Between the upper end of the tube A² and the said sleeve H is placed the coiled spring J, which acts to lift the rod E and all parts connected therewith after the rod has been depressed by pressure upon the handle D.

The handle D fits over the rod E, sleeve H, spring J, and upper end of the tube A² like a sleeve and incloses the same, and it is held to the upper end of the rod E by means of the nut j. (Shown clearly in Fig. 2.)

As above described, the rod E is loose in the tube A², and is of less diameter than the internal measurement of the tube, as shown in Fig. 2, so that when forced down by pressure on the handle it will yield to accommodate or conform to the arc described by the connection of the said rod to the tumbler when the latter turns on its central pivot.

Having thus described my invention, what I claim as new, and desire to secure by Letters Patent, is—

1. The stamp-canceler comprising a main plate provided with a handle and parallel cheek-pieces, in combination with a tumbler, a rod connected thereto, and blocks held between the cheek-pieces in ways and connected to the tumbler, whereby the downthrust of the handle will move the said blocks in a straight line between the cheek-pieces, substantially as described.

2. The plate A, having projection G and tumbler F pivoted thereto, and the rod E, attached to the tumbler, in combination with the blocks B B', connected to the tumbler on opposite sides of its pivot, substantially as described.

BENJAMIN SUMMERS.
